UNITED STATES PATENT OFFICE

120,943

DESIGN FOR A SLIPPER OR SIMILAR ARTICLE

Curt Wolfelt, New York, N. Y.

Application March 18, 1940, Serial No. 91,022

Term of patent 7 years

To all whom it may concern:

Be it known that I, Curt Wolfelt, a citizen of the United States residing at New York, in the county of New York and State of New York, have invented a new, original, and ornamental Design for a Slipper or Similar Article, of which the following is a specification, reference being had to the accompanying drawing forming part thereof.

The figure is a perspective view of a slipper showing my new design.

I claim:

The ornamental design for a slipper or similar article, substantially as shown.

CURT WOLFELT.
